RAIL SPIKE PULLER

Filed June 1, 1926

Patented Nov. 22, 1927.

1,650,096

UNITED STATES PATENT OFFICE.

ELMER E. SARR, OF HURON, OHIO.

RAIL-SPIKE PULLER.

Application filed June 1, 1926. Serial No. 113,011.

This invention relates to improvements in spike pullers.

The primary object of this invention is the provision of a spike, bolt, or nail puller, which is of a very compact nature, and which may be conveniently operated, with ease, to exert a powerful pull in a vertical direction, to draw a spike or the like straight out from its socket.

10 A further object of this invention is the provision of an improved spike pulling device, having an operating claw which pulls or exerts a force upon a spike in alignment with the spike, for the extraction of the same; the device embodying a powerful operating cam lever means to exert a powerful pull upon the claw with but little manual exertion.

20 Other objects and advantages of this invention will be apparent during the course of the following detailed description.

In the accompanying drawing, forming a part of this specification, and wherein similar reference characters designate corresponding parts throughout the several views,

Figure 1 is a side elevation of the improved spike puller, showing the same in position at the start of a spike pulling operation.

Figure 2 is a sectional view showing details of the improved spike puller, immediately after the spike has been pulled, and showing the discharge of the pulled spike from the device.

Figure 3 is a front elevation of the details of the improved spike puller, showing the parts in position at the start of a spike pulling operation.

40 Figure 4 is a cross sectional view taken substantially on the line 4-4 of Figure 3, showing more particularly the frame and a cam construction thereon for receiving the spike claw and operating lever.

45 Figure 5 is a perspective view of a spike socket end of the claw.

Figure 6 is a view showing the manner in which a special attachment may be used with the improved spike puller, for withdrawing spikes from between main and guard rails.

Figure 7 is a view showing the use of the attachment illustrated in Figure 6.

50 In the drawing, wherein for the purpose of illustration is shown only a preferred embodiment of this invention, the letter A

may generally designate the spike puller, which may comprise a frame B; spike claw C slidably mounted in the frame B; and claw operating means D.

60 The frame B is of course of any approved reinforced construction, and the same is of a special design, which will make the same convenient for portability, and yet designed to stand the forces which will be placed 65 thereon. The same includes a relatively shallow supporting base 10, which is ordinarily placed directly on the top surface 11 of a tie 12, or ground surface, but which may rest upon the top surface of a rail 13, 70 as is illustrated in Figure 6 of the drawing. The base 10 at the front end thereof is provided with the spaced vertically upstanding gibs or guide standards 16 and 17, having the vertical space 18 therebetween opening at the front of the frame B, and said standards 16 and 17 being grooved at their facing sides, at 20 and 21 respectively, preferably for the entire length thereof, to accommodate the reduced lugs 23 at the opposite sides of the spike head socket end 25 of the claw C, which will be subsequently 75 described, to guide said claw C in a rectilinear path between and along the guide standards or gibs 16 and 17.

80 At its rear end the base 10 is provided with a batter head 27, against which a person may hammer in order to force the spike head into the socket 30 of the claw spike head socket end 25, as will be subsequently 85 described.

85 The frame B furthermore comprises the cam supporting rails 35 and 36 at opposite sides thereof, connected at their forward ends integral with the guide standards 16 and 17, preferably intermediate the ends of said guide standards; said cam supporting rails 35 and 36 extending downwardly from their connection with the guide rails, for connection at their lower ends to the 100 batter head 27 of the base 10. At the inner sides of the rails 35 and 36, arcuated cam flanges or shelves 40 and 41 are preferably provided, extending from immediately adjacent the guide standards 15 and 16 respectively, and at their rear ends terminating short of the base 10, as illustrated in Figure 2 of the drawing. Upon the upper surfaces of these arcuated cam shelves 40 and 41 the operating lever D is adapted to 105 operate to pull the spike claw C upwardly in proper manner.

The frame B may furthermore include the guard rails 45, above the cam rails 35 and 36, which are connected at their forward ends to the guide standards 16 and 17 respectively, extending rearwardly and downwardly for connection to the said cam rails 35 and 36, as illustrated in Figure 2 of the drawing; said guard rails 45 forming an abutment against which an operator 10 may place his foot, in a guarded relation from the operating mechanism D.

Referring to a further description of the spike pulling claw C, the same includes the narrow elongated substantially flat shank 55, 15 which is rectangular in cross section, and which at the lower end has the spike head socket end 25, and which at opposite sides thereof has the reduced lugs 23 thereon which slidably extend snugly into the guide 20 grooves 20 and 21 to guide the vertical rectilinear movement of the claw as it is moved upwardly. The socket 30 is formed by providing spaced inwardly extending flanges 56 and 57, which are adapted to grip the head 25 of the spike F, as can readily be understood, and the socket 30 is open at the front of the claw C; the flanges 56 and 57 preferably being beveled to permit the same to be hammered to place beneath the head of the spike. 30 by hammering against the batter end 27 of the base 10, in a manner which is obvious.

Referring to the operating means D, the same preferably comprises an integral L-shaped lever 60, which at the lower end 35 thereof provides the arcuated cam engaging lever portions 61 and 62, which are of identical formation, as illustrated in Figure 2 of the drawings, the same being spaced from each other throughout their length, and providing convex lower surfaces 64 which are adapted to ride upon the top convex surfaces of the cams 40 and 41. The operating lever 60 furthermore includes the lever portion 63 which may be of any approved length, either 40 providing an attaching shank, or a socket for receiving a relatively long bar therein, or the bar may be formed rigid as a part of the lever portion 66. In the specific example shown the lever portion 66 is in the form 45 of a socket, and it extends in a general line at right angles to the cam operating lever portions 61 and 62, and is of course integral therewith. In the space 68 immediately adjacent the juncture of the spaced cam lever 50 portions with the lever portion 66, said lever portions 61 and 62 are provided with transverse aligning openings 69 for receiving a pin 70, which also extends through an upper apertured end of the body 55 of the spike 55 claw C, as is illustrated in the drawing, and thus the L-shaped lever 60 is pivotally connected at the juncture of the portions 61-62 and 66 with the upper end of the claw C.

The socket portion 66, in the specific instance shown is provided with a socket open-

ing 75 therein for receiving the lower end of a relatively long bar 76, which may be the conventional standard lining bar. In lieu of such a socket the lever portion 66 may constitute the bar 76 itself, or may 70 be formed rigid therewith, or the lever portion 66 may be merely a shank for receiving the socket on the lower end of a bar. These are merely alternative constructions which are within the mechanical ability of anyone 75 skilled in this art to apply; it being preferred to have a detachable connection of the bar 76 with the L-shaped lever 50, or to make the spike pulling device portable.

As a reinforcing feature of the L-shaped operating lever 60, the free ends of the cam engaging lever portions are connected with the forward end of a connecting brace bar portion 80, which extends in a divergent relation with the lever portions 61 and 62, and at its opposite end 81 the same is connected integral with the lever portion 66, above the juncture of the lever portions 61-62 and 66, as is illustrated in the drawings. This reinforces the substantially right angled portions 64 and 66, and connects the free ends of the spaced lever portions 61-62 in a stable relation. A spike knock-out projection 87 is formed integral or rigid with the free ends of the lever portions 61-62, in 90 transverse relation therewith, normally extending downwardly when the lever is in a position about to start the drawing of a spike, and which moves forwardly and into engagement with the spike after the spike has been pulled, to knock the spike out of the claw socket 30, in a manner which is well illustrated in Figure 2 of the drawing, and which can readily be understood.

Referring to an operation of the invention, the base 10 is applied as above described on a ground surface or on the tie, and the base is then forced towards the spike until the head of the spike is received in the claw socket 30. In this position of parts the operating lever 60 is positioned with the portion 66 vertical, and the lever portions 61-62 are positioned substantially horizontal with the convex surfaces thereof in engagement with the forward ends of the cams 40 and 41. After the bar 76 has been applied in the lever portion 66, the operator draws the same rearwardly, and this starts the elevation of the claw C; the convex edges of the lever portions 61 and 62 operating on the cams 40 and 41, and incident to the radii upon which the convex edges of the said cam lever portions 61 and 62 are formed, and incident to the formation of the cams, as the lever 60 is further rocked in order to extract the spike, said cam lever portions 61 and 62 will permit the leverage to be increased. That is, the fulcrum points of the lever portions 61 and 62 on the cams will move farther away from the guide 120 125 130

standards 16 and 17 as the claw is vertically moved upwardly, to increase the leverage action, and thereby producing a powerful pull which increases for the major length of extraction of the spike F, and until the spike is substantially withdrawn, when the fulcrum of the lever portions 61 and 62 moves along the cams toward the vertical guide standards 16 and 17, and when the spike is entirely withdrawn the knockout projection 87 will enter the open rear end of the socket 30 to engage the upper end of the spike F and knock the same from the claw C as illustrated in Figure 2.

In event the improved spike puller is used for pulling spikes between closely positioned rails, such as illustrated in Figures 6 and 7, a special extension 90 is used, which includes an elongated body 91, having a head 92 at the top thereof adapted to fit in the pocket 30, with the body 91 depending downwardly, and at the lower end said body 91 is provided with a spike head receiving socket 93 exactly similar to the socket 30 above mentioned, for receiving the head of a spike 94 which is positioned between said closely positioned rails, as illustrated in Figures 6 and 7, and with which attachment 90 the spike 94 may be readily withdrawn; the base 10 of the frame B in this instance resting upon the top of a rail 13.

From the foregoing description of this invention it is apparent that a novel type of spike puller has been provided, which will operate to efficiently withdraw spikes from rails.

Various changes in the shape, size, and arrangement of parts may be made to the form of invention herein shown and described, without departing from the spirit of the invention or the scope of the claims.

I claim:

1. In a spike puller the combination of a supporting frame, a claw slidably guided by the supporting frame, a lever movably connected with the claw, and cam means carried by the frame which the lever engages in order to elevate the claw for spike pulling.

2. In a spike puller the combination of a supporting frame having a convex cam thereon, a claw, and a lever movably connected with the claw having a convex portion for engagement with the convex cam in order that upon movement of the lever the claw will be elevated for pulling a spike or the like.

3. In a spike puller or the like the combination of a supporting frame having a cam thereon, a spike receiving claw slidably guided for rectilinear movement in said frame, and a substantially L-shaped operating lever pivotally connected with the claw having a cam engaging portion to one side of the

pivot, and an operating lever portion at the other side of the pivot.

4. In a spike pulling device the combination of a supporting frame, a spike gripping claw directly guided in its movement by the frame, an operating lever pivotally connected with the claw, and cam means including engageable cam portions carried by the frame and lever by means of which upon movement of the lever the pivot connection of the claw and lever will be moved in a straight line during elevation or lowering of the claw.

5. In a spike puller the combination of a supporting frame having guide standards thereon, a claw having a spike head socket therein and a body slidable in the guide standards for rectilinear movement therein, a cam connected with the frame, and lever means including a portion adapted to ride over the cam with a shifting fulcrum so that by movement of the lever means the claw will be elevated.

6. In a spike extracting device the combination of a supporting frame, a claw, an operating lever movably connected with the claw, cam means upon which the operating lever moves to elevate and lower the claw, and means to engage the spike after it has been withdrawn by the claw to knock the same from the claw.

7. In a spike puller the combination of a supporting frame, a claw slidably guided by the frame for rectilinear movement having a socket therein for receiving a spike head, a substantially L-shaped operating lever pivotally connected intermediate its ends to said claw, and cam means supported by the frame upon which the lever may rock in order to elevate the claw.

8. In a spike puller the combination of a supporting frame having a guide way therealong, a spike receiving claw slidably movable along said guideway, an L-shaped lever pivoted intermediate its ends with said claw, said lever and frame having convex engaging surfaces to permit rectilinear elevating or lowering of the claw during movement of the lever, and a spike extractor arm carried by the lever for cooperatively knocking the spike from the claw when the lever has been moved to a position where the claw has withdrawn a spike.

9. In a spike puller the combination of a supporting frame including side standard portions provided with vertical guide ways therein, a claw including a socket head for receiving the spike and having lugs extending into said guide ways for vertically guiding the movement of the claw in a rectilinear path, a cam rigid with the frame, and a substantially L-shaped operating lever pivoted intermediate its ends to the claw opposite the socket head thereof, including a lever portion with a convex edge for op-

erating on the cam whereby upon rocking of the lever the claw will be elevated for spike extraction.

10. In a spike puller the combination of a frame comprising a base, spaced upstanding standards having guideways facing in the space therebetween, said frame including upper spaced supporting rails connected with said standards and extending for connection to the base at the opposite end of the base from said standards, arcuated cams on said rails extending into the space therebetween, a claw having a lower head with a socket therein for receiving the head of a spike, said head having oppositely extending lugs for slidable reception in the guideways of said standards to permit the claw to move upwardly between the standards in a rectilinear line, a substantially L-shaped 20 operating lever including a handle portion and a cam engaging portion provided with a convex edge, said portions of the lever being arranged substantially in right angular relation and adjacent their juncture being pivotally connected to the upper end of the claw, the convex edge of the cam engaging lever portion being adapted to ride on the cam so that upon rocking of the L-shaped lever the claw may be moved upwardly for spike extraction.

11. In a spike puller the combination of a frame comprising a base, spaced upstanding standards having guideways facing in the space therebetween, said frame including upper spaced supporting rails connected with said standards and extending for connection to the base at the opposite end of the base from said standards, arcuated cams on said rails extending into the space therebetween, a claw having a lower head with a socket therein for receiving the head of a spike, said head having oppositely extending lugs for slidable reception in the guideways of said standards to permit the claw to move upwardly between the standards in a rectilinear line, a substantially L-shaped 40 operating lever including a handle portion and a cam engaging portion provided with a convex edge, said portions of the lever being arranged substantially in right angular relation and adjacent their juncture being pivotally connected to the upper end of the claw, the convex edge of the cam engaging lever portion being adapted to ride on the cam so that upon rocking of the L-shaped lever the claw may be moved upwardly for spike extraction.

12. In a spike extracting device the combination of a supporting frame, a claw movably guided by the supporting frame, having a socket for receiving a spike therein, an operating lever movably connected with the claw, cam means upon which the operating lever moves to permit movement of the claw to withdraw the spike, and means on the lever to engage the spike after it has been withdrawn to knock the same from the socket of said claw.

13. As an article of manufacture an operating lever for spike pullers comprising a substantially L-shaped body including an operating handle lever portion and a cam engaging lever portion arranged in substantially right angular relation with the handle lever portion, the cam engaging lever portion having a convex edge, a brace connecting the free edge of the cam engaging lever portion with the handle lever portion intermediate the ends of the latter, and a knock-out projection extending transversely from the free end of the cam engaging lever portion in projecting relation beyond the convex edge thereof.

14. In a spike pulling device the combination of a supporting frame, a claw guided by the frame during movement, lever means connected with the claw, cam means on the frame which the lever means engages to move the claw upwardly upon rocking of the lever means on said cam means, said claw including a spike head receiving socket 95 therein, and a detachable extension unit for the claw including a head for rigid disposition in said socket of the claw and at the opposite end thereof having a spike head receiving socket therein of the same formation 100 as the first mentioned socket.

ELMER E. SARR.
